UNITED STATES PATENT OFFICE

JOHN A. ZAREKO, OF BROOKLYN, NEW YORK

DESIGN FOR A COAT AND HAT HANGER OR SIMILAR ARTICLE

Application filed August 25, 1931. Serial No. 40,924. Term of patent 14 years.

To all whom it may concern:

Be it known that I, JOHN A. ZAREKO, a citizen of the United States, residing at Brooklyn, county of Kings, and State of New York, have invented a new, original, and ornamental Design for a Coat and Hat Hanger or Similar Article, of which the following is a specification, reference being had to the accompanying drawings, forming a part thereof, and in which:

I claim: The ornamental design for a coat and hat hanger or similar article, as shown.

JOHN A. ZAREKO.
